PITCHER'S RUBBER

Paul S. Madsen, Bethany, Conn., assignor to The
Seamless Rubber Company, New Haven, Conn.,
a corporation of Connecticut

Application October 7, 1948, Serial No. 53,197

5 Claims. (Cl. 273—25)

1

This invention relates to pitchers' rubbers or plates used in playing the game of baseball.

The ordinary pitcher's rubber or plate in use at the present time consists of a slab or mat of elastic material, such as rubber, that is relatively thin and requires securing means engaging the same and the underlying earth for holding it in place. There are various objections to this form of slablike rubber, among which are the difficulty of providing satisfactory anchoring means, and the fact that the slab does not remain level but is likely to project upwardly at one or more edges owing to the action of dirt which works in under the margins of the slab.

One of the objects of the present invention is to overcome these drawbacks.

Another object is to improve the anchoring of the pitcher's rubber, and provide a rubber which stays flat and level.

Another object is to provide a pitcher's rubber which is more durable than previous articles of this type, and in which the life of the article is very notably extended owing to the fact that, by changing the position of the rubber in the ground, new surfaces can be presented after the surfaces initially used become worn by the spikes of the players' shoes.

In the accompanying drawing:

Fig. 1 is a perspective view of a pitcher's rubber embodying my improvements, showing it embedded in the ground and ready for use;

Fig. 2 is an enlarged section on line 2—2 of Fig. 1;

Fig. 3 is an end view of the article as it appears prior to installation;

Fig. 4 is a section on line 4—4 of Fig. 3;

Fig. 5 is a side view of a modified form on a smaller scale; and

Fig. 6 is a section on line 6—6 of Fig. 5.

In its general nature the rubber illustrated in the drawing, instead of being in the form of a slab, has what might be termed a block shape or billet shape. The block is elongated and hollow, having a bore extending lengthwise from end to end, and the cross section of the block is square, so that there is created an article having four elongated flat faces each of which has dimensions corresponding to the upper face dimensions of the ordinary pitcher's slab. This article is preferably made of rubber, although the term rubber is used in a broad rather than in a restricted sense. The block is embedded in the earth so that in the installed position one of the elongated faces is flush, or substantially flush, with the surrounding earth.

2

In the drawing, the rubber is indicated generally at 10, and in Figs. 1 and 2 its installed position is shown. The surrounding earth is indicated at 11, and at 12 is indicated the longitudinal opening or bore of round cross section. In the form shown in Figs. 1 to 4, inclusive, this bore is provided within a reinforcing sleeve 13, which is snugly received within a rubber body 14 that constitutes the body of the block. It is preferable to continue the rubber of body 14 across each end of the sleeve or liner 13 so as to conceal the end of the sleeve. This extended or continued part of the rubber end face is indicated at 15, and this extension is slightly lapped over the interior of the sleeve, as indicated at 16 in Fig. 4, the effect being that the end face of the block is planar throughout, and that the end edge of the sleeve is received and held in an annular groove provided in the rubber material.

The purpose of the sleeve is to increase the stiffness of the structure. The sleeve illustrated is made of a mixture of asbestos fibers and a suitable binder, molded in tubular form and having considerable stiffness. It may, however, be made of other material, such as metal, for example.

When the block is embedded in the manner shown in Figs. 1 and 2, a certain amount of the surrounding earth or soil will enter the bore of the block, and this is indicated in Fig. 2.

The rubber block of square cross section is provided in uncured condition. The reinforcing sleeve is then introduced into the bore, and the article is then vulcanized in any appropriate way. However, the particular procedure in manufacturing can be varied as conditions may require.

In the form shown in Figs. 5 and 6, the reinforcing sleeve or liner is omitted. Here the rubber block 17 has a round bore 18 within which is placed a reinforcing plug 19. This reinforcing plug may be of any suitable material; in the form shown it is made of concrete. It will be noted that the plug is shown as having end portions which project substantially beyond the end faces of the rubber body. This article is embedded in the earth, and when so embedded the body portion of the plug or inner reinforce gives added weight for purposes of stability, and the end portions of the plug or core extend into the earth in a manner to serve as anchoring members, resisting any tendency to displacement of the block from its assigned position.

In the forms shown, the bore or opening at the end face of the block may be of a diameter of approximately four inches. Where, as in the present case, the width of the block face is six

inches, it will be seen that the provision of the bore considerably lessens the weight of the block as compared to a solid block, without making it too light for purposes of stability. On the other hand, the weight is considerably increased in comparison to the slab form of plate or rubber, so as to overcome the need of fastening the article in place by underlying securing devices such as nails, screws and the like.

The present article is much more securely anchored than previously used articles, and the rubber remains flat and level, which is very desirable. The weight of the block is quite sufficient to prevent teetering, although, on the other hand, the weight is not greater than is required for the purpose of firm, satisfactory anchoring. Making the longitudinal opening of round cross section obviously makes the article highly resistant to compressive forces, but openings of other profiles can be used if desired.

The ground around the block should be well tamped down, and this, in connection with the weight of the block, obviates the need for underlying securing means.

In the use of pitchers' rubbers the longitudinal edges presented to the feet of the pitcher are worn down by the spikes on the pitcher's shoes. When the edges of a plate of slab form become badly worn, replacement is necessary, it being then required that the securing devices be removed and a new slab installed. With the present form of rubber, the durability and longevity are much greater by reason of the better anchoring and also because of the fact that, to compensate for wear, the block can be turned on its longitudinal axis to present new corners or edges to the feet of the pitcher. Supposing, for example, that in use the pitcher's feet unduly wear down the forward edge or corner of the block, in other words, that edge or corner disposed toward the home plate, the necessary adjustment can be made by giving the block a quarter turn, so as to embed the worn edge and present a new edge. This quarter-turn rotation can then be repeated at least twice for the purpose of providing fresh new edges at the front of the block. The rear edge, of course, is subject to wear, but in any case it will be obvious that the permissible adjustment of the block by turning on its axis greatly increases the scope and longevity of the article in comparison to the forms of plate or rubber previously used.

Referring, for example, to Fig. 2 of the drawing, it will be apparent that the elongated member adapted to be embedded in the ground has a flat upper surface adapted to be positioned substantially flush with the ground, said member having adjacent at least one of the lateral margins of said surface a part or element projecting downwardly to a substantial extent to prevent dirt from working in under said member adjacent said margin, the member being of closed cross-sectional form, and said downwardly projecting part or element presenting a second flat surface of the same area as said upper surface.

When the block is placed in a cavity of the pitcher's mound in the manner shown in Fig. 2, each of the additional playing faces of the same area as the upper playing face is disposable in said cavity substantially flush with the ground upon lifting the block from the cavity, giving it the required turn about its longitudinal axis, and then lowering it.

Two embodiments of the invention are illustrated, but it will be apparent that additional modifications and changes in the details may be made without departing from the principles of the invention or the scope of the claims.

What I claim is:

1. A pitcher's mound having a ground cavity, and a pitcher's rubber of solid block formation received in said cavity and having a flat playing face substantially flush with the ground and also having at least one additional playing face below the ground level, said rubber having a through longitudinal opening therein to receive a substantial amount of the surrounding earth or other material for properly anchoring said rubber within the ground.

2. A pitcher's mound having a ground cavity, and a pitcher's rubber of square cross section and with a continuous wall having four playing faces, said rubber received in said cavity with any one of said playing faces exposed and positioned substantially flush with the ground, and said rubber having a through longitudinal opening therein to receive a substantial amount of the surrounding earth or other material for anchoring said rubber within the ground.

3. The subject-matter of claim 1 wherein the material received within said longitudinal opening is in the form of a reinforcing plug or core of concrete or other material to provide added weight for purposes of stability.

4. The subject-matter of claim 1 wherein the material received within said longitudinal opening is in the form of a reinforcing plug or core with its end portions projecting from said block and extending into the surrounding earth to serve as anchoring members for said block.

5. The subject-matter of claim 1 wherein the through longitudinal opening for receiving a certain amount of earth or other material is reinforced by a stiffening sleeve member.
